(57) **CLAIM**

The ornamental design for a housing portion of a power inverter, as shown and described.

DESCRIPTION

FIG. 1 is a front and left side perspective view of the new design for a housing portion of a power inverter.

FIG. 2 is a front elevational view of the new design of FIG. 1.

FIG. 3 is a top plan view of the new design of FIG. 1.

FIG. 4 is a bottom plan view of the new design of FIG. 1.

FIG. 5 is a right side elevational view of the new design of FIG. 1; and,

FIG. 6 is a rear elevational view of the new design of FIG. 1.

In the figures, the thin solid lines appearing within the boundaries of the housing portion are shading lines used to indicate its exterior contoured surfaces. The broken lines in the figures are for illustrative purposes only and do not form part of the design sought to be patented.
